UNITED STATES PATENT OFFICE.

WILLIAM C. CUTLER, OF GLENDALE, CALIFORNIA, ASSIGNOR TO ISABELLA C. CUTLER,
OF GLENDALE, CALIFORNIA.

MULTIPLE-VENDING MACHINE.

Application filed November 28, 1925. Serial No. 72,048.

The present invention relates to vending machines and pertains more particularly to selective and multiple vending machines.

One object of the invention is to provide 5 a vending machine in which a single coin may serve a plurality of vending units so that a purchaser may obtain any selected one of a number of contained articles by dropping a coin in the slot and simultaneously indicating the desired article.

It will be understood in the consideration of this invention that a vending machine is quite unprofitable unless some provision is made for detecting and eliminating 15 bogus coins, slugs and other articles commonly employed for illegally obtaining merchandise from such machines. When it is required that several different articles be selectively vended by one machine it is 20 necessary to make a selective or multiple machine. The selective types of machines embody a single coin slot and a single slug detecting mechanism. In selective machines there is either a movable magazine or a movable indicator. The magazine, or indicator, 25 as the case may be, is first moved to bring the desired article into position. Then the coin is deposited, and then an operating lever must be moved to discharge the contents. The entire act of selecting and purchasing an article requires several movements on the part of the purchaser. If a 30 plurality of vending units are arranged side-by-side a coin slot and slug eliminator must be employed for each vending unit. Such a machine is quite as expensive to build as a plurality of single vending machines.

Another object of this invention therefore 40 is to provide a machine in which the article may be selected and discharged with less number of moves on the part of the purchaser.

Still another object of the invention is to provide a multiple machine which embodies 45 a plurality of vending units and only one coin slot and slug eliminator, with means whereby a coin deposited in a single slot may be caused to operate any selected one of the units.

50 Still other objects and advantages of my invention will appear hereinafter.

I have illustrated my invention by the accompanying drawings, in which:—

55 Figure 1 is a perspective view of one embodiment of my invention.

Figure 2 is a view in vertical section thereof seen on a line 2—2 of Fig. 1.

Figure 3 is a view in section thereof seen on a line 3—3 of Fig. 2.

Figure 4 is a view in section thereof seen 60 on a line 4—4 of Fig. 3.

In carrying out my invention in this embodiment I employ a casing 6 having a plurality of vertical partitions 7 providing a plurality of compartments 8 in which articles 65 9, to be vended may be arranged in stacks. The stacks rest on spaced shelves 10 and the shelves are so arranged that a coin 11 in moving horizontally below a stack of articles will engage the rear edge of the 70 lowermost article and withdraw it from under the others of the stack. Forwardly of the casing there is provided a hood 12 which encloses a chute 13 thru which the articles may gravitate to an opening 14.

Under each compartment there is provided 75 a coin carriage 15 having a coin holding slot 16. The coin carriage travels over a horizontal wall 17 and over an aperture 18; there being one aperture for each compartment 80 and one coin carriage for each compartment. When a coin has been carried to the aperture it falls thru such aperture into an enclosed coin space 19 below the wall 17. By the time that a coin has reached an aperture 85 18 it has dislodged the lowermost package of a corresponding stack so that the package slides down the chute into the reach of the purchaser.

This arrangement of parts is common to 90 many vending and multiple vending machines, and such arrangement together with various means to prevent return of the coin while the coin is in place, is well known in the art and needs no further description to 95 render my invention clear to those skilled in the art.

Each carriage is moved by a pull rod 20 that passes out thru the front of the machine to terminate in a button 21. In conformance with a salient feature of my invention, altho I am not limited to this feature, I provide for each coin carriage being slightly lower than the one next preceding it. I provide a coin chute 22 leading to a 100 coin tester and slug eliminator 23; the purpose of this eliminator being to detect bogus coins and slugs and prevent them from reaching the coin carriages. The coin chute, or more correctly the coin tester, dis- 105 110

charges into a slightly inclined horizontally directed runway 24 which runs behind successive compartments and terminates in a coin returning slot 25 externally of the casing. Each coin carriage has the coin receiving slot and the runway is provided with a lower opening or slot 26 above each coin carriage. The slot in each carriage provides for a coin falling thru to the coin carriage. Each carriage also has solid portion 27 immediately behind the coin receiving slot. The runway also has a circular cut-away portion 29 over each coin carriage so that a coin having fallen into the coin carriage may be moved forwardly without interference from the walls of the runway. Behind each carriage there is a spring 30 which holds the carriage advanced so that the solid portion of the carriage comes below the corresponding slot in the runway. Thus a coin passing thru the coin tester will run down the runway; the solid portion of each carriage preventing the coin from coming to rest, and eventually the coin will reach the coin return opening. If any carriage is moved rearwardly so that the coin receiving slot thereof comes below the corresponding slot in the runway, a coin will fall into that carriage and will be held from going further. Obviously the coin will stop in the first carriage which it enters, and will remain there until the carriage is moved to discharge a package.

To operate this machine, the purchaser selects the stack from which he desires an article, by pressing on the button which is below that stack. The contents of the machine are of course visible thru the translucent panel 32, commonly provided in vending machines. At the same time that he presses the button in with one hand he may use his other hand to insert a coin in the coin slot. Thereby the act of selecting the article and dropping the coin is, practically speaking, a single operation requiring the use of both hands, and the operation is accomplished almost instantly without appreciable thought or effort.

Assuming that the button which is pressed is that nearest the end of the machine; the coin will fall first on the first carriage but will merely rebound from that carriage and will start to roll down the inclined runway. Successively it will encounter the solid parts of successive coin carriages and will continue in its course until it reaches the said last carriage, or in any other case until it reaches the first carriage which has its slot alined with the runway. Now the coins fall into the slot in the carriage. The purchaser pulls the button outwardly. The coin is carried forwardly by the carriage and it projects above the carriage and encounters the lowermost package in the manner common to many other vending machines. The pack-

age is discharged and the coin drops in the coin receiving space from which it can be removed only by a person having a key to the door 35 of said compartment.

If a coin is placed in the machine without depressing a button it will return to the coin returning slot where it may be had by the person placing the coin in the slot. If a coin is caused to enter a carriage, and said coin is allowed to stay there unbeknown to a subsequent patron of the machine such coin will not clog the entire machine but will merely act to direct the next coin to some point beyond it, or to the coin returning opening.

It will be apparent now that I have provided a simple, quickly operated, selective or multiple vending machine in which one coin testing slot will serve a plurality of coin-operated discharge mechanisms, and whereby any article may be selected, paid for and discharged all in a short interval of time and without requiring any particularly thoughtful moves on the part of the purchaser, and whereby the acts of selecting, paying and discharging, are so closely linked as to make it as expedient as if only one move were made to carry out all steps of purchasing an article; and

While I have shown and described a specific embodiment of my invention I do not limit myself to any specific construction or arrangement of parts and may alter same as I desire without enlarging the scope of my invention within the appended claims.

I claim:

1. In a vending machine, a runway adapted to convey a coin and provided with a plurality of successively arranged openings thru which such coin may fall, an article delivery coin carriage below each opening normally disposed to close said opening against a coin; each carriage also being movable to allow a coin to pass thru the opening into the carriage.

2. In a vending machine, a coin slot provided with a plurality of successively arranged coin emitting openings, a coin carriage below each opening, each carriage having a solid portion movable into and out of registration with the corresponding coin emitting opening, and each carriage having a coin receiving slot disposed to aline with the corresponding opening when the solid portion is moved out of registration with the corresponding coin emitting opening.

3. In a vending machine, a single coin slot, a runway into which said slot discharges provided with a plurality of coin emitting apertures, article delivery coin carriages, one below each aperture, each carriage having a solid portion and a coin receiving slot, and each carriage being movable to dispose either its solid portion, or its slot, into registration with the correspond-

ing coin emitting aperture; for the purpose set forth.

4. In a vending machine, a single coin slot, a runway into which said slot discharges, provided with a plurality of coin emitting apertures, article delivery coin carriages, one below each aperture, each carriage having a solid portion and a coin receiving slot, and each carriage being movable to dispose either its solid portion, or its slot, into registration with the corresponding coin emitting aperture; for the purpose set forth, a pull-out handle for each coin carriage, and a wall below each carriage provided with a slot thru which a coin may fall from the slot of said carriage when said carriage is pulled out to bring the slot thereof into registration with the slot in the corresponding wall.
5. In a vending machine, means for holding a plurality of stacks of articles in a lineal arrangement; so that the lowermost article of one stack is below the lowermost article of a preceding stack, walls, one stepped below the other progressively of the stacks so that there is provided such a wall a given distance below each stack, coin carriages, one for each wall slideable over the corresponding wall and provided with a vertical coin slot open at both its upper and lower terminations whereby the wall will act to hold the coin in place in the slot of the corresponding carriage, each wall provided with an aperture thru which the coin may fall from the slot of the corresponding carriage when the slot is moved into registration with the corresponding aperture, the

slot in a carriage and the corresponding wall below it arranged to co-act to hold a coin so that the coin will protrude from the upper open end of the slot of the carriage to engage and dislodge the lowermost article of a stack as said carriage is moved forwardly toward the corresponding aperture, an inclined runway passing successively behind each stack of articles and having a plurality of coin emitting openings one for each carriage and so disposed as to allow a coin to fall into the slot of the corresponding carriage when the slot of said carriage is aligned therewith; each carriage having a solid portion arranged to prevent a coin from passing thru the corresponding coin emitting opening of the carriage when same is in normal position, springs, one for each carriage normally holding same in such position that the solid portion of the corresponding carriage is registered with the corresponding coin emitting opening of the runway, and a pull-out handle to each carriage, said handle movable against said spring to align the slot of the corresponding carriage with the corresponding coin emitting opening of the runway; each handle further movable to move the carriage forwardly to convey a coin forwardly to dislodge the lowermost article of a stack while said coin is being moved into registration with the corresponding slot in the underlying corresponding wall.

In testimony whereof I affix my signature.

WILLIAM C. CUTLER.
